UNITED STATES PATENT OFFICE.

LOUIS PAGE AND LOUIS WEBER, OF BROOKLYN, NEW YORK.

CURTAIN-FIXTURE.

SPECIFICATION forming part of Letters Patent No. 297,627, dated April 29, 1884.

Application filed January 18, 1884. (No model.)

To all whom it may concern:

Be it known that we, LOUIS PAGE and LOUIS WEBER, citizens of the United States, residing at the city of Brooklyn, in the county of Kings 5 and State of New York, have invented new and useful Improvements in Curtain-Fixtures, of which the following is a specification.

Our invention relates particularly to curtain-fixtures applicable to curtains arranged 10 to slide endwise along their supporting-bars, and is an improvement upon our Letters Patent No. 291,928, dated January 15, 1884, which principally describes the curtains as suspended from balls or knobs which slide inside of 15 an extensible bar while the curtain is being withdrawn or replaced.

The objects of our improvements are to provide, first, an adjustable bracket for supporting the curtain-bar, the bracket being formed 20 of two or more pieces sliding along each other, so that the length of the bracket can be changed, and thereby the distance from the curtain to the wall or jambs varied, as desired, such brackets also forming the end caps of the bar; second, for the construction of the sections of an 25 extension curtain-bar, with guiding cleats or V-shaped grooves, which prevent their rotation upon each other and preserve the continuity of their slit in which the necks of the 30 curtain-supporting hooks slide; third, for the construction of the "master-balls," to which the free ends of the curtains are attached, in such a manner that when the length of the bar is being changed these balls can be shifted 35 along the cord from the outside without dismounting the bar and cord; fourth, for providing curtain-bars with hooks or eyelets, by which a lambrequin or other auxiliary ornamental drapery can be suspended; fifth, for 40 curtain-supporting devices arranged to roll instead of slide within the bar of improved construction, as described; sixth, for bolting the cord-guiding roller-frames to the brackets, instead of fastening them to the curtain-bar; 45 seventh, for improved sectional sockets which confine the ends of the curtain-bar; eighth, for an improved device for suspending the curtain-clamps from the ball-knobs or rollers which rest within the bar; ninth, for a device 50 preventing excessive extension of the bar and consequent sagging and disfigurement. We attain these objects by the mechanism illustrated in the accompanying drawings, in which—

Figure 1 is a longitudinal section, in plan, of such an extensible curtain-bar, supported by 55 extensible brackets drawn into their shortest dimensions, the brackets being formed of two pieces each, as shown. Figs. 2 and 3 represent an end view and a section of a curtain-bar-supporting socket formed of two parts. 60 Fig. 4 represents a vertical section of a part of the bar, and of a clamp with its improved attachment to a supporting-ball; also a device for preventing excessive extension of the bar, a modification of which is shown in Fig. 6. 65 Figs. 5, 8, and 9 are vertical transverse sections of the curtain-bar with improved master-balls, to which the free ends of the curtains are attached. Horizontal sections of the master-ball represented by Fig. 5 are shown 70 in Fig. 1. Fig. 7 is likewise a vertical cross-section of the bar, and represents the improved rollers and hook combination which support the curtain, and of which horizontal sections are shown in Fig. 1. Fig. 10 represents an 75 elevation or side view of the bracket D, Fig. 1, extended to its maximum length. Figs. 11 and 12 represent horizontal sections of such an extension-bracket, formed of three pieces at maximum and minimum length, Fig. 13 80 representing a vertical cross-section of the middle piece thereof; and Fig. 16 is a side view or elevation of such three-part bracket. Figs. 14 and 15 represent a two-part bracket, the free end of which is an open eye or half-loop, 85 in which the end of the curtain-bar rests.

Similar letters refer to similar parts throughout the several views.

The curtain-bar, Fig. 1, is composed of the central part, A, and the two end pieces, A'A', 90 which telescope into the central part, all these pieces being slit open at the bottom, as shown, so as to allow the shanks of the hooks G to pass into and slide along the bar and fasten to the curtain-supporting balls or rollers, to which 95 they are permanently attached, except as to the master-balls F F, with which their connection is made, as herebelow described.

To prevent these sections A A' A' of the bar from turning upon each other when made cylindrical, which would obstruct the endwise sliding of the necks of said hooks G in said slot, each section A A' A' is formed with a V-groove, as shown in Figs. 4 to 9, so that the V-groove of the central piece, A, will fit into 105 the V-grooves of the end sections, A'A': Half-

round or other indentations, so fitting into each other, would serve the purpose. Such an extension curtain-bar need not necessarily be straight, but can be made curved, so as to conform to an opening arching vertically or horizontally. A separate application for improvements in such bars is contemplated.

The extensible brackets D D', Fig. 1, serve as end pieces or caps to the bar, as well as for supports therefor. For that purpose the free parts thereof end in sockets or caps d', which confine the outer ends of bar-sections A'. The shank e of the roller-frame E passes centrally through the bottom of the cap d', as shown, and is there confined by nut e', as well as by the wooden core of the ornamental end knob, W, which is screwed upon the protruding screw-threaded shank e, the latter being square within the cap end. One of the two pieces composing the bracket D or D' is formed with a slot, as d² in the several figures. A screw, d³, passes through that slot and screws into the other piece, d⁴, which has raised edges d⁵ d⁶, so as to form a trough, into which the slotted end of piece d² fits, and is therein confined laterally by said screw d³ and vertically by said raised edges d⁵. This piece d² is fastened to the jamb by screws passing through its wing d⁷.

Fig. 1 shows the wing d⁶ of bracket D in a plane with its sliding parts d² d⁴, and the wing d⁶ of bracket D' at right angle to the bracket, so as to admit of its attachment to jambs facing the curtain-bar. Figs. 14 and 15 represent such an extension-bracket provided with an open loop at the free end for the support of the bar, instead of the socket or cap d'. Figs. 11, 12, 13, and 16 represent such a bracket formed of three pieces, so as to attain greater range of extension, Figs. 11 and 12 being horizontal central sections, Fig. 16 a side elevation, and Fig. 13 a vertical cross-section and in part end view of the central piece, M.

The improvements to the master-balls F F, to which the free ends of the curtains are attached, are shown in Figs. 1, 4, 5, 8, and 9. The lower part of these balls resembles a hemisphere, f, which is surmounted by a solid bail, f', pierced at right angles by two eyelets, one for each cord. The shank g of the hook G screws centrally through the hemisphere and the bail. In Figs. 4 and 5 this shank g is provided with a disk or flange, g', which enters a corresponding recess in the lowest portion of the ball, as shown. Parallel to this hook-shank g a hole is formed in the ball, extending from one of said eyelets to the said recess for said flange g', and a pin, g'', Fig. 5, plays loosely in that hole. The cords being passed through the eyelets, the ball is attached to one of the cords by screwing the hook G into the ball until the flange g' forces the pin g'' firmly against the cord, and thus confines the same. The same object is attained, as represented in Fig. 8, by placing the eyelets and cords vertically one over the other and clamping the ball to the lower cord by screwing the shank

g directly against it, the flange g' in that case being omitted. In Fig. 9 the eyelets and cords are side by side, but so as to bring one of them directly over the shank g. The dismemberment of the cord by the screw motion is prevented by the loose pin g'', intervening between the shank g and the cord. With this construction the flange g' is also unnecessary. By either of these constructions the main purpose—that of being able to shift the master-balls along the cord, when changing the length of the bar, without dismounting the bar and the cord—is accomplished, the cord being released or clamped by manipulating the hook G, which extends below the bar. The lower flange, g', which is rounded off on the top edge, is to prevent the entering of the hook G through the slot into the bar when the cords are unduly resisted.

To bring the clamp H, Figs. 4 and 5, close to the bar, and centrally under the same, it is attached to the hook G by a bail, h, attached to the spindle which pivots the two wings of the clamp H, as shown. The drawings represent the hook G as at right angles to the spindle of clamp H. The entering of the hook into the bail h is facilitated by giving the bail at the top a quarter-turn loop, so that the hook stands parallel to the spindle.

Figs. 1 and 7 show improvements in the curtain-supporting balls or devices not used as master-balls. The improvement consists in sustaining the curtain by two rollers, R R, similar in shape to a hemisphere flattened at the pole, and mounted upon the spindle r'. Around the center of this spindle, between the rollers R R, the shank of the hook G is looped, and is extended upward through a bail, r, attached to the ends of said spindle, as represented. This bail r, together with the hook-shank which passes through it, separates and guides the two cords.

The curtain-bar-supporting socket represented in Figs. 2 and 3 is formed of two parts, as shown in Fig. 2. The lower part remains attached to the jamb, while the upper one is removed to dismount or mount the bar. The division between the two parts is preferably made obliquely at an angle of about forty-five degrees with a horizontal line, so that the socket can be placed close to the top arch or beam without interference with the mounting of the bar. The cylindrical part of the socket, at its edge farthest from the jamb, is made with an inward flange, S, which serves to retain endwise the outward flange upon the end cap, d', of the bar, as represented in Fig. 3. As an excessive extension of the bar would cause it to sag, deforming its contour and injuring the ends of the sections, means are provided for preventing such undue extension, as shown in Figs. 4 and 6. Fig. 4 shows a spring-wire, K, fastened in the V-groove of the middle section, A, under the reinforcing ring a'. To the free end of this spring K a pin, K', is attached, which passes through the opening K² in the section A, and during normal ex-

tension of the sections rests upon the inner section, A', as shown in Fig. 4. This inner section, A', is provided with an opening, a², which, when the extension becomes excessive, 5 comes under pin K', which enters therein, and thus checks further extension. Another method of accomplishing this object is represented in Fig. 6. In this case the two openings K² a² are the same; but the spring K is dispensed with, the pin K' passing simply through the re-enforce ring a'. This method is particularly applicable when the re-enforce ring a' is ornamented by a central knob, as shown, and to insure the falling of the pin K', its top end 15 is made heavy by making it a part of such ornament, as represented.

Figs. 1 and 7 represent hooks or eyelets P, attached to the front and under side of the curtain-bar for the purpose of suspending 20 therefrom a lambrequin or other supplementary and ornamental drapery. These eyelets are preferably fastened to the re-enforce rings a'.

The ends of the bar-sections telescoping into 25 each other may be lined with soft fibrous material, cemented on, for the double purpose of preventing scratching the polished surfaces in the act of changing the length of the bar, and to obtain a tight fit at the lapping ends 30 of the sections.

To the bar-supporting cap d' of the brackets may be added an outwardly-extending cap or socket, d⁸, Fig. 11, for chambering the neck of the ornamental knob W, instead of screwing 35 the latter upon the shank e. This method is particularly applicable to the larger curtain-bars, and admits of placing the shank e eccentrically.

What we desire to claim and secure by Letters Patent is—

1. As a support for a curtain-bar, a bracket formed of two or more flat pieces placed edge-wise up and down, one or more of the pieces with edges raised laterally, and one or more of 45 the pieces slotted, so as to admit of their sliding upon and stiffening each other and of being clamped together laterally, substantially as set forth.

2. As a support for a curtain-bar, an extension-bracket formed of two or more pieces arranged to slide upon each other endwise, one of such pieces forming the end cap of the curtain-bar, as set forth.

3. The combination, with a curtain operated endwise along its support, of sockets 55 which support and confine the ends of the curtain-bar, each socket being divided circumferentially into two parts, and provided with a flange which retains endwise the end cap of the bar, substantially as set forth.

4. The combination, with a curtain arranged to slide endwise along its supporting-bar by means of cords, of master-balls F F, attached to such cords, each ball provided with an eyelet 65 for each cord, with a central screw-tapped hole at right angles to and between such eye-

lets, a smooth hole opening into one of said eyelets, in which hole a pin, g², slides freely, together with a curtain-supporting hook, G, the threaded shank of which is screwed into 70 said central tapped hole, and is made to control the position of said pin g² and its impingement upon the cord by means of a flange, g', upon said hook, which hook G is operated from the outside of the bar, substantially as 75 set forth.

5. The combination, with a curtain arranged to travel endwise along its supporting-bar by means of cords, of master-balls, each ball provided with an eyelet and a curtain-supporting hook, the shank of which hook screws into 80 such ball, and by its entry into the ball causes the cord in such eyelet to be clamped, substantially as set forth.

6. The combination, with an adjustable extension curtain-bar formed of two or more cylindrical pieces telescoping into each other, of longitudinal grooves or other indentations which match so as to prevent the telescoping sections from turning upon each other, substantially as set forth. 85

7. The combination, with an extension curtain-bar composed of two or more pieces sliding along each other, of a lug or pin, K', and corresponding openings, K² and a², operating 95 substantially as set forth in guarding against excessive extension of the bar-sections.

8. The combination, with a curtain arranged to move endwise along its supporting-bar, of a curtain-clasping clamp, H, suspended from 100 the bar by a hook or eyelet, G, attached to the clamp by a bail, h, the ends of which are fastened to the spindle pivoting the two parts of the clamp, substantially as set forth.

9. The combination, with a curtain operated endwise along its supporting-bar, of hooks or eyelets P, attached to the under and front side of such bar for the support of a supplemental lambrequin or other ornamental drapery, substantially as set forth. 105

10. The combination, with a curtain operated endwise along its supporting-bar, of curtain-supporting hooks and rollers arranged to travel along such bar, each set being formed of two rollers, R R, their spindle r², and the hook 115 G, with its shank looped centrally around spindle r² and piercing at its upper end the bail r, which bail is looped around the ends of spindle r², the whole operating substantially as set forth. 120

11. The combination, with a curtain arranged to be operated endwise along its supporting-bar by means of cords, of cord-guiding rollers attached by their frames to the bottom of the caps covering the ends of the 125 bar, substantially as set forth.
